REFRIGERATION APPARATUS

Matthew P. Fugle, Oak Park, Ill., assignor to
Larkin Refrigerating Corporation, Atlanta, Ga.,
a corporation of Georgia

Application May 16, 1932, Serial No. 611,460

5 Claims. (Cl. 257—252)

This invention relates to refrigeration in general and particularly to highly practical cooling units adapted for use in all types of refrigerators including storage refrigerators, display case refrigerators and to standard type of storage refrigerators in which our units may be installed in combination with the usual refrigerant circulating systems.

An important object of my invention is the provision of metal fins which are detachably or permanently secured upon any refrigerant conduit, and which metal fins present the proper ratio of cooling surface to absorb heat.

A further object of my invention is the provision of a refrigeration apparatus comprising a refrigerant circulating system having a plurality of easily assembled and detachable absorbing fins which present a large area of cooling surface and which are cooled through conductivity from the refrigerant conveying pipes.

A further object of the invention is to provide metal heat absorbing plates which are inexpensively and easily attached to any old and existent refrigerant conveying line, thereby eliminating loss of the previous refrigerant circulating lines as well as cost of removal and cost of complex refrigerant units.

A further object of my invention is the provision of a refrigerant apparatus which may be easily and economically assembled or taken apart and in which the heat absorbing units are arranged in staggered or in line-assembled relation so as to contact the maximum volume of warm air circulating within the refrigerator.

On the drawing:

Fig. 1 is a side elevation of a section of one of my preferred units illustrating the intermediate mounting of the springs between the fins mounted about a refrigerant pipe.

Fig. 2 is an end elevational view showing the joined channel supporting units in cross section.

Fig. 3 is a fragmentary view taken from the right of Fig. 2 and illustrating the outside of adjacent channel members and showing the pipes in cross section.

Fig. 4 is an enlarged fragmentary and elevational view illustrating 3 of the fins upon a section of refrigerant pipe and showing how the molten tin or other fusible metallic means will adhere and bind the springs and fins with respect to the refrigerant pipe.

As shown on the drawing:

Fig. 1 shows a typical form of a smaller size refrigeration unit embodying the principles of our invention. A cooling refrigerant is circulated

in a well known manner through a continuous pipe 10 shown in Fig. 1, one end of which pipe is securely connected to the outlet side of a refrigerant expansion valve which in turn communicates with the refrigerant supply tank (not shown). The lower end of said pipe is connected to a compression pump which reduces the refrigerant to liquid form, as is well known in the art. The refrigerant conveying pipe 10 is bent so that different portions thereof are substantially parallel 10 and form a cooling unit of any desirable shape or size for convenient mounting within refrigerators or the like in such a manner that a minimum amount of space is taken up.

A plurality of channel shaped mounting plates 15 11, each of which has one lateral edge thereof turned inwardly parallel to the main flat side thereof are successively superposed to form standards securely mounting the refrigerant conveying line as shown in Fig. 1. Each of the 20 mounting members 11 has its double edge cut away to form a semi-circular recess for convenient reception of the refrigerant pipe 10. The mounting members 11 are mounted so that the recesses of adjacent mounting plates will coincide and lie about and secure the refrigerant pipe 10 at various points in substantially the same plane. The opposite sides of the channel shaped mounting plates 11 have a plurality of apertures 25 which receive short bolts 12 to secure adjacent 30 mounting members 11 in superposed position as shown in Figs. 2 and 3.

The circulation of a cooling refrigerant through the pipe 10 keeps the pipe 10 cold and causes it to absorb heat in the atmosphere or liquids with 35 which it comes into contact. Because the cooling surface of the pipe 10 is very limited compared to the air circulation thereabout and the heat to be absorbed, it is highly desirable to increase such heat absorbing surface by means of metal 40 fins which will be cooled by induction from the refrigerant conveying pipe 10. I therefore provide a plurality of metal fins 13 which are easily mounted about the refrigerant pipe 10, the form or shape of which may be varied in accordance 45 with the requirements of each particular case.

It is highly desirable that these fins may be easily and inexpensively mounted to permit economical installation thereof either upon a previously installed refrigerant pipe or a newly installed refrigerant pipe.

The form of fin shown in the drawing permits installation of my highly efficient and modern heat absorbing units in a previously installed refrigerating plant having only the refrigerant 55

pipe surfaces as the sole heat absorbing means, thereby saving the cost of such previous installation and of considerable labor.

I desire that it be understood that the form 5 of fin heretofore described may be manufactured in various ways and shapes. For example, a substantially circular metal stamping having an aperture through which the refrigerant line runs may be satisfactorily used when attached 10 in one of the methods I describe herein.

The figures of the drawing show a highly satisfactory form of my invention which employs flat metal fins 13 having central apertures which are successively slipped over the end of a pipe, and 15 a resilient coil spiral spring 31 is slipped on said pipe immediately behind each fin. Each of said springs fit snugly about the pipe and the ends thereof contact respective adjacent fins 13 to hold the fins in uniform spaced apart position 20 to any angle desired with respect to the refrigerant pipe 10. The angle desired may be regulated by bending the ends of the springs to a certain desired angle to the longitudinal axis of the spring, which when mounted in the manner 25 shown will hold the fins at the same angle. When a coil is formed I dip it into molten metal such as tin or lead which, after solidifying, forms highly satisfactory bond and holding means between portions of each spring and the refrigerant pipe.

30 A highly important feature of the construction shown is that the springs increase the conductivity of heat of the fins, particularly when the usual frost has formed about the refrigerant pipe and covers the springs and pipe. The contact of the ends of the springs with the fins permits quicker absorption of heat and increases the conductivity of the cold from the refrigerant pipe. The last fin at each end of each unit comprising a series of adjacent mounted fins may be 35 held against outward movement either by a suitable ring or clamp (not shown) or by soldering or otherwise fusing the metal on the pipe as indicated at 27 of Fig. 4 and in contact with the outer surface of the end fin. Such attaching 40 means will likewise permit removal if it is desired to disassemble the unit or replace either the fins or the pipe because of deterioration or the like.

I am aware that many changes may be made 45 and numerous details of construction may be

varied through a wide range without departing from the principles of this invention, and I therefore do not purpose limiting the patent granted thereon otherwise than necessitated by the prior art.

5 I claim as my invention:

1. In a refrigerating plant, a refrigerant pipe having portions thereof in different planes; a plurality of metal heat absorbing fins removably mounted thereon; and coil springs about said refrigerant pipe between each pair of adjacent fins adapted to hold said fins in spaced apart position.

10 2. In a refrigerating plant, a refrigerant unit comprising horizontally arranged piping adapted to circulate a refrigerant; a plurality of heat absorbing fins mounted about said piping, yieldable members about said piping and interposed between adjacent fins to hold said fins in position, and supporting standards for each refrigeration unit.

15 3. A refrigerant unit adapted to be connected for circulation of a refrigerant therethrough, refrigerant piping arranged in parallel relation, a plurality of metal heat absorbing fins in spaced apart relation on said piping, and a plurality of annular yieldable members about said piping, and adapted to hold said fins in position, and fusible metallic means securing said fins and yieldable members in substantially permanent relative position.

20 4. For use in a refrigerant plant, a refrigerant pipe having portions thereof in different planes; a plurality of metal heat absorbing fins removably mounted thereon; and a coil spring about said pipe and between adjacent fins, the ends of said coil springs contacting adjacent fins and adapted to increase the conductivity between said fins and said refrigerant pipe.

25 5. In a heat refrigerating plant, a heat absorbing unit comprising a refrigeration pipe; said pipe having different sections thereof in different planes; a plurality of supporting units adapted to be connected together in superposed relation to form mounting means for said pipe; a plurality of heat absorbing fins mounted on said pipe; means for yieldably mounting said fins in spaced apart relation on said pipe; and metallic means adapted to hold said last mentioned means in 30 position with respect to each other.

35 MATTHEW P. FUGLE. 50
